UNITED STATES PATENT OFFICE.

GEORGE C. VAN RODEN, OF PHILADELPHIA, PENNSYLVANIA, ASSIGNOR TO
J. E. CALDWELL & CO., OF SAME PLACE.

DESIGN FOR A BADGE.

SPECIFICATION forming part of Design No. 28,165, dated January 18, 1898.

Application filed September 25, 1897. Serial No. 653,057. Term of patent 14 years.

to all whom it may concern:

Be it known that I, GEORGE C. VAN RODEN, citizen of the United States, residing in Philadelphia, Pennsylvania, have invented a certain new and useful Design for a Badge, of which the following is a specification.

My design for a badge is fully illustrated in the accompanying drawing, which is a face view of the badge.

The essential feature of the design is the circle having within it the representation of a spinning-wheel and above the circle a crown. Within the circle is the representation of a spinning-wheel. Surrounding the circle is a sunburst, and mounted on the sunburst and surrounding the circle is a series of floral rosettes, and above the circle is a crown sur-

rounded by a floral arch. On each side of the crown and extending back of the sunburst is the representation of two flags, one an American flag and the other an English flag, the whole forming the design clearly illustrated in the accompanying drawing.

I claim—

The design for a badge as herein described and as illustrated in the accompanying drawing.

In testimony whereof I have signed my name to this specification in the presence of two subscribing witnesses.

GEORGE C. VAN RODEN.
